INTEGRAL TRANSFORMER ELECTROMAGNETIC TRANSDUCER

David F. Brower, Torrance, and Raymond Howard Griest, Los Angeles, Calif., assignors to Hughes Aircraft Company, Culver City, Calif., a corporation of Delaware

Application April 4, 1955, Serial No. 499,142

10 Claims. (Cl. 179—100.2)

The present invention relates to electromagnetic transducers, and more particularly to an improved electromagnetic head for recording, reproducing or erasing information stored as states of magnetization on lengthy magnetizable record bodies.

In copending U. S. patent application, Serial No. 454,551, filed September 7, 1954, and entitled, "Electromagnetic Transducer," by David F. Brower, there is disclosed a novel form of "single-turn" electromagnetic transducer or head characterized by an operating efficiency and ease of fabrication heretofore unknown in the art. The single turn feature of the transducer substantially contributes to the efficiency of coupling between the transducer and record body. However, because the single-turn has a low impedance, it is generally necessary to provide a transformer for coupling the transducer to an external circuit.

The use of an external coupling transformer, such as that shown in the cited Brower application, considerably increases the overall space required for the transducer combination. In addition, the use of a transformer external to the transducer requires that two separate magnetic structures be utilized with a consequent increase in the losses, and a consequent reduction in efficiency.

It is, therefore, an object of the present invention to provide an improved electromagnetic transducer or head having an integral coupling transformer provided therein.

Another object of the present invention is to provide an electromagnetic transducer and coupling transformer in which a common magnetic core is utilized for both transducer and transformer.

A further object of the present invention is to provide an improved electromagnetic transducer having a coupling transformer provided therein characterized by an inherent simplicity and ease of fabrication heretofore impossible of achievement.

Still another object of the present invention is to provide an electromagnetic transducer with a coupling transformer built therein having a novel core configuration which permits the same magnetic core to be utilized for both transducer and transformer, and yet provides an optimally efficient electrical and magnetic structure for each function.

Yet another object of the present invention is to provide an electromagnetic transducer and transformer having a common core structure, a portion of which serves as the core for the transducer and another portion as the core for the transformer, which provides for optimum coupling of the transducer and the transformer with a minimum of stray leakage flux.

An electromagnetic transducer, according to the present invention, comprises a transformer core, a first endless winding disposed on the core to form an open turn about the core with a segment of the winding disposed to have an edge flush with the surface of an outer edge of the core, and a second winding wound over a portion of the first winding.

2

The novel features which are believed to be characteristic of the invention, both as to its organization and method of operation, together with further objects and advantages thereof, will be better understood from the description considered in connection with the accompanying drawings in which an embodiment of the invention is illustrated by way of example. It is to be expressly understood, however, that the drawings are for the purpose of illustration and description only, and are not intended 10 as a definition of the limits of the invention.

Fig. 1 is a perspective view, partly in section, of the electromagnetic transducer and transformer of the present invention;

Fig. 2 is a view in perspective of a conductive shim 15 which may be utilized in the transducer of the present invention;

Figs. 3a and 3b are elevational views illustrating various shapes of the transducer pole faces to adapt them for different record bodies;

Fig. 4 is a perspective view of the embodiment of Fig. 1, illustrative of flux and current paths within the transducer; and

Fig. 5 is a view in perspective of a multiple transducer array, according to the present invention, which includes 25 a plurality of individual transducers for recording a plurality of parallel magnetic tracks.

Referring now to the drawings, wherein like reference characters designate like or corresponding parts throughout the several figures, there is shown in Fig. 1 one embodiment of the electromagnetic transducer or head and transformer of the present invention. As shown in Fig. 1, the combined head and transformer includes first and second oblong core pieces 10 and 11, having adjacent pole faces 110 and 111, respectively. Core pieces 10 and 11 are in contact with each other along a line 16 remote from their pole-face ends, and are separated at their pole faces by a first flat ribbon conductor 12 which passes between the core pieces, thereby defining a recording gap in the core structure formed by the core pieces.

Ribbon conductor 12 substantially encircles core piece 10 at its pole-face end, the portion of ribbon 12 lying between the core pieces having an edge 13 disposed in the plane defined by the adjacent edges 14 and 15 of pole faces 110 and 111, respectively. A second flat conductive ribbon 17 substantially encircles core piece 10 in a region intermediate the region covered by conductor 12 and the line of contact 16 between core pieces 10 and 11, while the ends of ribbon 17 and conductor 12 are interconnected by means of a pair of flat conductive bars 18 and 20, respectively. Conductive bars 18 and 20 extend along and parallel to core piece 10, and are superposed along at least a portion of their width, the superposed portions, as well as the ends of conductor 12 and ribbon 17, being insulated from each other by insulating material, represented as a strip 21.

Ribbon 17 serves as the primary winding of a coupling transformer 22, the secondary winding of the transformer comprising a plurality of turns of relatively fine wire wound thereover and depicted as coil 23. The ends 60 or terminals of coil 23, numbered 24 and 25 respectively, are utilized for interconnecting the transducer with an external circuit, not shown, for alternately exciting the transducer or deriving signals therefrom. Core piece 11, which has one side in intimate contact with conductor 12, has a recess 19 cut therein opposite coil 23 to permit the portion of the core extending beyond the coil to make contact along line 16 with a similar portion of core piece 10 extending through ribbon 17 and coil 23.

It should be noted that while conductor 12, conductive bar 18, ribbon 17, and conductive bar 20 form a closed current conductive path in the order enumerated, the current conductive path formed by the parts does not

encircle core piece 10, but rather itself forms an open turn about the core piece. The significance of this arrangement of the parts from an operational standpoint will be discussed more fully hereinafter.

Considering now the fabrication of the transducer and transformer thus described, core pieces 10 and 11 preferably are of a material having high magnetic permeability, low magnetic retentivity, and high specific resistivity. Some magneto-ceramic materials display these properties, and accordingly the core pieces may be of magneto-ceramic material, such as the ferrite materials. Core pieces 10 and 11 may initially be fabricated to identical dimensions to as close tolerance as required, using techniques well known in the art, following which recess 19 having appropriate dimensions may be cut in core piece 11. The use of core pieces having a high specific resistance obviates the necessity of including insulation between the core pieces and the normally current conductive elements of the transducer such as conductor 12 and ribbon 17. Thus, each of these elements placed in intimate contact with the core structure, thereby increasing the magnetic efficiency of the transducer and transformer.

Flat ribbon conductor 12 may be of copper or silver, or similar highly conductive material, of 1 to 2 mils thickness, the thickness of the conductor serving to establish the width of the recording gap in the magnetic structure. Alternatively, the ribbon may be of any other thickness, the selected dimensions being based on considerations well known in the magnetic recording art. Conductive ribbon 17 and conductive bars 18 and 20 may be composed of similar material of the same thickness, if desired. The efficiency of the transformer portion of the transducer may be considerably enhanced and stray flux paths substantially reduced by dimensioning the width of conductive ribbon 17 and coil 23 so that the coil completely covers the ribbon.

While conductor 12, ribbon 17 and bars 18 and 20 have been described as separate parts and may be so fabricated, the interconnection of the parts and their final assembly in the form shown in Fig. 1 may be considerably simplified by initially fabricating the parts from a single piece of highly conductive material, shaped substantially as shown in Fig. 2. As shown in Fig. 2, conductive shim or band 26 is a single piece of substantially rectangular highly conductive material having an aperture 27 cut out therein. Shim 26 has a length corresponding to the desired final distance between edge 13 and the edge of ribbon 17 adjacent contact line 16, and a width at least slightly greater than the circumference of core piece 10. Aperture 27, which may have a width substantially corresponding to the width of the adjacent sides of core pieces 10 and 11 and a length selected to produce the desired width for each of conductors 12 and ribbon 17, is positioned with respect to the side edges of shim 26 so as to fall between the adjacent sides of core pieces 10 and 11 when the parts are assembled in their final form. It should be noted that aperture 27 need not be placed in the middle of shim 26, when it is desired that conductive bars 18 and 20 overlap along a side of core piece 10 other than the side opposite the side adjacent core piece 11.

While edge 13 may have a length corresponding to the width of shim 26 as indicated by the dashed lines in Fig. 2, the corners of the shim preferably are cut away to produce an additional pair of edges 28 and 29 disposed at an angle with respect to edge 13. These edges are preferably cut to provide that edge 13 have a length corresponding to the width of the recording gap in the core structure, and are particularly useful to reduce the effect of current flowing in these portions of the shim on the record body. Shaping the shim in this manner also reduces the danger of shorting the edges of the shim if the pole-face end of the transducer is to be shaped or ground following assembly.

Considering now the assembly of core pieces 10 and 11 and shim 26, core piece 10 may first be placed on shim 26 with its pole-face edge 14 adjacent shim edge 13 and the core piece lying on the shim parallel to its length. The portions of shim 26 not covered by core piece 10 may then be folded about the core piece, with a strip 21 of insulating material interposed between the overlapping portions of the shim in order to electrically insulate the overlapping portions of the shim from each other. Coil 23 may then be wound about core piece 10 and shim 26, and core piece 11 may then be placed in proper abutting relationship with the assembly thus formed. The resulting transducer may be encapsulated in plastic, or placed in any other type housing which may retain the parts in appropriate relationship.

For recording intelligence, a translatable record body may be caused to pass successively over pole face 110, edge 13, and pole face 111, electrical current representing the data to be recorded meanwhile being applied to the transducer by means of leads 24 and 25 attached to coil 23. The transducer of the present invention may be used either for contact recording, that is, with the transducer in contact with the record body, or for non-contact recording, that is, with the transducer merely in close proximity to but spaced from the record body. Preferably, the record body may be moved at right angles to the portion of shim 26 which is between pole faces 110 and 111. The transducer may be employed in a similar manner for reading or picking up information which has already been recorded, or for erasing, in accordance with systems well known in the art.

After completing the assembly of the transducer, the pole-face ends may be shaped to any desired contour, thereby improving the operational characteristics of the transducer. For example, as shown in Fig. 3a, where the transducer is to be employed for recording on a cylindrical drum surface 31, the pole-face end 32 of the transducer may be ground to a concave shape of approximately the same radius as that of the drum. Such shaping has been found to be of value when the transducer is utilized in non-contact recording, and of especial value when the transducer is utilized in contact with the drum surface. Where the transducer is to be employed in conjunction with a flexible magnetizable tape 33, the pole-face end 32 of the transducer may be ground generally in V shape, and the tape drawn across the pole-face end of the drum in tension, as shown in Fig. 3b. Under such conditions, folds and creases in the tape tend to be "ironed out" as the tape passes across the transducer, and the reliability of operation is substantially improved.

Referring now to Fig. 4, there is shown a diagram illustrative of the flux paths and current paths flowing in the transducer of Fig. 1 when a record body 33 is moved past the pole-face end of the transducer. As shown in Fig. 4, motion of the previously recorded magnetic areas on record body 33, in the direction of the arrow, past the pole-face end 32 of the transducer will cause stray flux to flow into the transducer. The high permeability of core pieces 10 and 11 will cause this stray flux to tend to encircle conductor 12 as shown by the heavy-dashed line 34. The direction of flux flow will arbitrarily be assumed to be as represented by the arrows on the line. As the record body moves, flux 34 will tend to cut conductor 12, inducing a current therein, the path of current flow being depicted by the lightly dotted line 35, the direction of flow again being indicated by the arrows. The current path 35 will follow a path of flow through conductor 12, down bar 18, through ribbon 17 and return to conductor 12 through bar 20. It will be seen that the current flowing through the ribbons and the bars passes around core piece 10 in ribbon 17 in a direction opposite to the direction of current flow through conductor 12. The current flowing through ribbon 17 will tend to produce flux in the core pieces following the path depicted

by heavy-dashed line 36 with the direction of flow again being shown by the arrows. This flux will practically all be confined to the core pieces due to their relatively high permeability as compared to the conductive parts of the transducer and free space. Flux 36 will in turn tend to induce currents in coil 23 as it intersects the coil. These currents may then be utilized in an external circuit by means of connections to coil ends 24 and 25.

It will thus be seen that the path of current in conductive shim or band 26, comprising conductor 12, bars 18 and 20 and ribbon 17, tends to flow about core piece 10 in a path substantially corresponding to the outline of a saddle disposed on core piece 10, where one hump of the saddle is disposed in the recording gap of the core structure and coil 23 is wound about another hump of the saddle-shaped conductive path.

It will be also be seen that flux 34 and flux 36 tend to traverse the regions of core pieces 10 and 11 intermediate conductor 12 and ribbon 17 in opposite directions, and, accordingly, this flux will tend to cancel in this region. In practice, a flux corresponding to a single turn times the current flowing in shim 26 will pass through the aperture. Since this flux will always have a small value, the reluctance of the magnetic path in this area need not be low and accordingly core pieces 10 and 11 need not be in contact in this intermediate region. In fact, where the transducer and transformer of the present invention is to be utilized at relatively high frequencies, aperture 27 in shim 26 may be omitted from the shim with no apparent reduction in the operating efficiency of the transducer.

By way of further explanation of the mode of operation of the present invention, it should be noted that any record body flux which tends to traverse the entire length of the core pieces passes through coil 23 in the same direction as the flux produced by the current flowing in ribbon 17, and accordingly, augments the current inducing flux produced thereby. While the presence of an aperture in conductive shim 26 contributes substantially to the performance of the transducer at low frequencies, at higher frequencies where the aperture is omitted, the path of stray flux from the record body may be considered to be from the record body into pole face 110, thence along the entire length of core piece 10, over to core piece 11 and then along the entire length of core piece 11, returning to the record body through pole face 111.

The advantages of the transducer of the present invention in manufacture and assembly over the prior art transducers will at once be readily apparent. In particular, the transducer may be readily scaled to any desired dimensions. Thus the transducer may be made as small as desired without unduly complicating either its fabrication or assembly. It will also be noted that the tolerance of the dimensions of the head is determined almost completely by the tolerance maintained in shaping the core pieces. Since these pieces are merely oblong rectangular pieces, their fabrication to close tolerances will present no unusual problems.

Similarly, it will be noted that a further advantage of the construction thus described is that the planeness of the active portion of conductor 12 in the gap between core pieces 10 and 11 is determined by the planeness of the portions of core pieces 10 and 11 abutting the conductor. Since the core pieces are essentially rigid elements, and may be readily machined to the planeness required, planeness of a high order may be imparted to conductor 12. The use of a malleable material, such as silver, for conductor 12, contributes to the achievement of this advantage, the ribbon readily conforming to the shape required when compressed between the two core pieces.

A further advantage of the present transducer is that the location of the gap with respect to the external mounting surfaces of the transducer is again purely a function of the shape of the core pieces, and since the core pieces have regular geometric shapes, their fabrication to a high order of accuracy, and consequently, the accurate posi-

tioning of the completed transducer with respect to the tape or drum, may be readily achieved.

Still another advantage of the embodiment of the transducer shown in Fig. 1 is that the width of the transducer is only slightly greater than the width of the track of the tape or drum. Accordingly, additional transducers may readily be placed closely adjacent to each other in order to provide for the recording of closely spaced parallel tracks on the same tape or drum. As will be more fully discussed hereinafter, the transducer of the present invention is particularly useful for such applications.

In operation the transducer and transformer of the present invention offers a number of advantages over conventional coil type transducers, as well as over the single-turn type transducers heretofore proposed. In particular shim 26, in addition to the current conductive functions heretofore set forth, performs a "self-shielding" function and substantially reduces stray flux which might otherwise arise where the transducer is of a relatively open-type construction. Where coil 23 has a width corresponding to the width of ribbon 17, the coupling between these two elements becomes unity for practical purposes, and accordingly, the transformer portion of the present invention produces practically zero stray flux. Besides reducing the effective inductance of the transducer-transformer configuration, the "self-shielding" properties also tend to contribute to the electrical isolation of the transducer from its surroundings due to the elimination of stray flux fields.

The transducer of the present invention is particularly useful where a plurality of transducers is disposed for simultaneously recording signals on a plurality of parallel record paths of a single tape or drum. A particular advantage of the present transducer in such applications is the fact that the means for mounting the transducers may additionally serve as shielding means for both the transducer and transformer.

An example of such a configuration which provides for two transducers for the parallel recording of two record tracks, is shown in Fig. 5. The transducer array of Fig. 5 includes first and second transducers 50 and 50', a common mounting and shielding block 51 and two retaining strips 52 and 52' for retaining the transducers within mounting and shielding block 51.

More particularly, mounting and shielding block 51 is a block of rigid conductive material such as copper or brass, having two slots, 53 and 53' in one edge thereof. Slots 53 and 53' are cut as by milling to a depth appropriate for positioning each transducer. The slots are of sufficient depth and width to receive transducers 50 and 50' respectively and accordingly include an additional cutaway for receiving the exciting coils of the transducers. After positioning the transducers within their respective slots, retaining strips 52 and 52' may be placed over each transducer and fastened, as by soldering or similar techniques in order to retain the transducers within their respective slots. The two retaining strips may be of material similar to block 51. A strip of paper or similar insulating sheet material may preferably be placed between the normally current conductive parts of the transducers, and block 51, and the retaining strips in order to prevent short-circuiting of the transducers.

Following assembly of the transducers, mounting block and retaining strips, the pole-face end of the assembly may be shaped by grinding to any desired contour for presentation to a tape or drum, as previously discussed. As shown in Fig. 5, the pole-face end may be generally of V-shape, as for example where the array is to be used for recording parallel tracks on tape.

The embodiments of the present invention thus described represent preferred embodiments. It should be understood, however, that numerous modifications may be made. For example, in Fig. 1, where conductive

bars 18 and 20 are shown as overlapping along a portion of their width, the bars may be placed adjacent to each other without substantially detracting from the performance of the present transducer. Similarly, while shim 26 has been described as a single shim of conductive material, the desired configuration may readily be achieved by depositing a conductive coating of appropriate shape directly on core piece 10, utilizing techniques well known in the art.

What is claimed is:

1. An electromagnetic transducer comprising a transformer core, a first endless winding on said core, said first winding being disposed about said core in such manner that the winding does not form a closed loop about said core, and a second winding wound over a portion of said first winding, said first winding including a segment disposed on said core in such manner as to have an edge flush with the surface of an outer edge of said core.

2. An electromagnetic transducer comprising a transformer core, a gap in the peripheral face of said core, a first winding on said core, said winding being endless, said endless winding being arranged about said core in such manner as to form an open turn about said core and having a portion of one edge disposed in said gap, and a second winding wound over said core and covering a portion of said first winding.

3. In combination in an electromagnetic transducer head, a magnetic core having record confronting surfaces with an air-gap therein for permitting travel of a record member therebefore, means defining a window to permit mounting an energizing coil on said core, a non-magnetic electrically conducting shield member having one portion filling at least a portion of said air-gap and another portion extending into a substantial portion of said window, said shield member being shaped to prevent the formation of a short-circuited turn about said core, and an energizing coil wound about said core and said another portion.

4. An electromagnetic transducer comprising: a first core piece, a flat band of conductive material encircling said first core piece, the ends of said band overlapping along one side of said first core piece, a sheet of insulating material for insulating the ends of said band from each other, said band having one edge disposed on said core in such manner as to be flush with the surface of an outer edge of said core, and an energizing coil wound over a portion of said band.

5. The electromagnetic transducer defined in claim 4, including a second core piece disposed adjacent to said edge of said band and said first core piece.

6. The electromagnetic transducer defined in claim 5, wherein said band has an aperture in the portion of said band lying intermediate said first and second core pieces, said energizing coil being dimensioned and disposed so as not to cover said aperture.

7. An electromagnetic transducer comprising: a pair of core pieces having adjacent pole faces; a flat ribbon conductor encircling one of said core pieces at its pole-face end, said ribbon conductor passing between the core pieces and being arranged to have an edge lying in a plane common to said pole-face ends; a second conductive ribbon substantially encircling said first core piece in a region remote from said pole-face ends; an energizing coil comprising a plurality of turns of relatively fine wire wound over said second conductive ribbon, and means for electrically interconnecting said ribbon conductor and said conductive ribbon.

8. The electromagnetic transducer defined in claim 7, wherein said last named means includes a pair of flat superposed conductors interconnecting said ribbon conductor and said conductive ribbon, said superposed conductors being electrically insulated from each other and being disposed along one side of said one of said core pieces.

9. In combination in an electromagnetic transducer head, a magnetic core having record confronting surfaces with an air-gap therein for permitting travel of a record member therebefore, means defining a window to permit mounting an energizing coil on said core, said window communicating with said air-gap, a non-magnetic electrically conducting shield member having one portion filling at least a portion of said air-gap and another portion extending into a substantial portion of said window, and an energizing coil wound about said core and said another portion.

10. In combination in an electromagnetic transducer head, a magnetic core having concave record contacting surfaces with an air-gap therein for permitting travel of a record member thereacross, means defining a window to permit mounting an energizing coil on said core, said window communicating with said air-gap, a non-magnetic electrically conducting shield member having one portion filling at least a portion of said air-gap and another portion extending into a substantial portion of said window, and an energizing coil wound about said core and said another portion.
